UNITED STATES PATENT OFFICE.

PETER BURD JAGGER, OF LONDON, ENGLAND.

GRINDING AND MIXING AND AGITATING MACHINE AND THE LIKE.

Application filed February 25, 1921. Serial No. 447,861.

To all whom it may concern:

Be it known that I, PETER BURD JAGGER, a subject of the King of Great Britain, residing at London, England, have invented 5 certain new and useful Improvements in and Relating to Grinding and Mixing and Agitating Machines and the like, of which the following is a specification.

The present invention relates to improvements in and relating to grinding and mixing and agitating machines and the like, and being particularly applicable to ball and like grinding and mixing and agitating machines and the like, as will be hereinafter 15 described in the application.

The present invention is essentially characterized by a tandem system of two or more receivers revolving alternately in opposite directions on a horizontal or substantially 20 horizontal axis, fixed partitions between the receivers serving as common heads or closures to the adjacent ends of the receivers, provision being made for end discharge from receiver to receiver and a final discharge at 25 the opposite end from where the feed enters.

The pass from one charged receiver to another may be controlled by a straight or curved plate slide normally closing an opening in a fixed partition which serves as a 30 common head or closure to adjacent ends of two receivers.

The receivers may be conveniently and advantageously mounted peripherally in suitably supported bearings which may have 35 inwardly projecting radial flanges or like to co-operate with outwardly projecting radial flanges or like on the receivers for connecting the receivers end to end, also to like bearings at the feed and discharge 40 ends of the system.

Drive of the receivers so that they revolve alternately in opposite directions may be variously effected. Gear wheels which drive 45 toothed rings on the receivers and are alternately driven by open and crossed belts respectively from a common main shaft to separate counter shafts serves well.

In mounting the tandem system of receivers there may be a general slope of the system towards the discharge end.

The method of feeding may be by a hopper and sloping passage through the feed-end or head of the system, and in some cases there may be provision for feeding as by a hopper 55 and passage through one or more or any of the partitions of the system, such additional

feeding provision stepping in for example if it is desired to add some other material or materials at some intermediate stage or stages in the treatment.

The system may be adapted in well known or appropriate manner for use as a tube mill, or as a ball or like mill or mixer or agitator, or as a combination of a ball and tube mill, or, otherwise, the tumbling of the 60 material due to revolving the receivers alternately in opposite directions may suffice either alone, or in conjunction with means, as a suitable liner, or radial or oblique ribs or shelves, to effect a desired mixing or incorporating operation.

The following is an example of mixing concrete by a machine under the present invention, firstly the stones are fed to the machine, then the sand, and then the cement. 75 The machine is started and sufficient water is then added. The stones and sand have a mill action on the cement and mixing and incorporating is accompanied by a simultaneous fine grinding action like or similar 80 to a tube or ball mill.

In passing from one charged chamber to another while the machine is continually or continuously being fed all chambers come finally under pressure so that there is a 85 drive through all chambers in a direction towards the discharge end and outwards to the moulds or otherwise wherever required.

The accompanying drawings shew by way of example a form of machine embodying 90 the present invention.

In the drawings, Fig. 1 is a side view, Fig. 2 a sectional view on the line $x-x$ of Fig. 1 shewing one form of plate slide, Fig. 3 is a view of a variant form of plate slide, 95 Fig. 4 is a diagrammatic view of the drive for the cylinders, and Fig. 5 an end view thereof.

As shewn by Fig. 1 the machine comprises a tandem system of cylinders 1, 2, 3 and 4 100 mounted so that the general slope of the system is towards the discharge end. The cylinders are mounted peripherally in suitably supported bearings 5 having inwardly projecting radial flanges 6 which co-operate 105 with outwardly projecting radial flanges 7 on the cylinders for connecting the cylinders end to end. The bearings 5 are on fixed partitions or plates 8 which serve as a common head or closure to adjacent ends of the 110 chambers 9 of the cylinders 1, 2, 3 and 4. Like bearings 10 are provided on the feed

end plate 11 and discharge end plate 12 of the system.

Drive of the cylinders so that they revolve alternately in opposite directions is effected by toothed rings 13 on the cylinders with which engage gear wheels 14, 14^a. The pinions 14, 14^a are alternately driven by open and crossed belts 15 and 16 respectively from a common main shaft to separate counter shafts 17 and 18.

The main feed is by a hopper 11^a and sloping passage 11^b through the feed-end plate 11 of the system. Additional feeding provision is provided by hoppers 19^a and 15 passages 20 through the partitions or plates 8.

Rollers 21 rotatably carried by shafts 22 form an external bearing system for the cylinders 1 to 4, rings 23 on the cylinders 20 bearing on the rollers 21.

The pass from one charged chamber to another is controlled in the machine illustrated by Figs. 1 and 2 by straight plate slides 24 working in openings in the fixed partitions 8. Fig. 2 shews one slide 24 in the open position whereby discharge from, for example, the cylinder 4 to the cylinder 3 can take place. The discharge takes place through a screen or grid 25 provided in the 30 slide 24, so that the size of the material passing from one chamber to the other is controlled, and in the case of working the mill with a filling of, for example, steel balls these are prevented from passing from one 35 chamber to the other during the passage of the material.

Fig. 3 shews a varied form of control for the pass in the form of a curved plate slide 26 having a screen or grid 27.

40 The final discharge takes place through an outlet 28 and a slide control 29 similar to the slides 24.

The slide control may be operated in any convenient way.

45 Supplemental means such as ribs 30 may be provided, in addition to the tumbling of the material due to revolving the cylinders alternately in opposite directions, for effecting a desired mixing or incorporating operation.

50 What I claim is:—

1. A machine for the purposes described comprising in combination a tandem system of receivers mounted so as to revolve alternately in opposite directions on a horizontal axis, means for imparting drive to the receivers, fixed partitions between the receivers, said partitions serving as common heads or closures to the adjacent ends of the receivers, means for allowing end discharge from receiver to receiver, a feed provision at one end of the system and a final discharge at the opposite end thereof.

2. A machine for the purpose described 65 comprising in combination a tandem system

of receivers mounted so as to revolve alternately in opposite directions on a substantially horizontal axis, means for imparting drive to the receivers, fixed partitions between the receivers, said partitions serving as common heads or closures to the adjacent ends of the receivers, means for allowing end discharge from receiver to receiver, a feed provision at one end of the system and a final discharge at the opposite end thereof. 75

3. A machine for the purposes described comprising in combination a tandem system of receivers mounted so as to revolve alternately in opposite directions on a horizontal or substantially horizontal axis, means for imparting drive to the receivers, fixed partitions between the receivers, said partitions serving as common heads or closures to the adjacent ends of the receivers, means for allowing controlled end discharge from receiver to receiver, a feed provision at one end of the system and a final discharge at the opposite end thereof. 80

4. A machine as claimed in claim 1 hereof having additional feeding provision intermediate between the primary feed and the final discharge. 90

5. A machine for the purposes described comprising in combination a tandem system of receivers mounted so as to revolve alternately in opposite directions on a horizontal or substantially horizontal axis, means for imparting drive to the receivers, fixed partitions between the receivers, said partitions serving as common heads or closures to the adjacent ends of the receivers, means for allowing end discharge from receiver to receiver, a feed provision at one end of the system and a final discharge at the opposite end thereof, and supplemental means in the receivers for assisting in the desired mixing or incorporating operation. 100

6. A machine for the purposes described having a plurality of hollow cylinders arranged as a tandem system, said cylinders revolving alternately in opposite directions on a horizontal or substantially horizontal axis, means for imparting drive to the cylinders, fixed partitions between the cylinders serving as common heads to the adjacent ends of the cylinders, slides in the fixed partitions normally closing openings in the said partitions and allowing controlled end discharge from chamber to chamber of said cylinders, a feed provision at one end of the system and a final discharge at the opposite end thereof. 110

7. A machine for the purposes described having a plurality of hollow cylinders arranged as a tandem system, said cylinders revolving alternately in opposite directions on a horizontal or substantially horizontal axis, means for imparting drive to the cylinders, fixed partitions between the cylinders serving as common heads to the adjacent 120 ends of the cylinders, slides in the fixed partitions normally closing openings in the said partitions and allowing controlled end discharge from chamber to chamber of said cylinders, a feed provision at one end of the system and a final discharge at the opposite end thereof. 125

ends of the cylinders, slides in the fixed partitions normally closing openings in the said partitions and allowing controlled end discharge from chamber to chamber of said 5 cylinders, a feed provision at one end of the system, a final discharge at the opposite end thereof, and additional feeding means through one of the fixed partitions.

8. A machine for the purposes described 10 having a plurality of hollow cylinders arranged as a tandem system, said cylinders revolving alternately in opposite directions on a horizontal or substantially horizontal axis, means for imparting drive to the cylinders, fixed partitions between the cylinders serving as common heads to the adjacent 15 ends of the cylinders, slides in the fixed partitions normally closing openings in the said partitions and allowing controlled end discharge from chamber to chamber of said 20 cylinders, a feed provision at one end of the system, a final discharge at the opposite end thereof, and additional feeding means through a plurality of the fixed partitions. 25 9. A machine as claimed in claim 6 hereof having the tandem system of cylinders mounted to have a general slope of the system towards the discharge ends.

10. A machine for the purposes described 30 having a plurality of hollow cylinders arranged as a tandem system, said cylinders revolving alternately in opposite directions on a horizontal or substantially horizontal axis, means for imparting drive to the cylinders, means for allowing controlled end discharge from chamber to chamber of said 35 cylinders, supplemental means for assisting in the mixing or incorporating operation, a feed provision at one end of the system and a final discharge at the opposite end 40 thereof.

11. A machine for the purposes described comprising in combination a tandem system 45 of receivers mounted so as to revolve alternately in opposite directions on a horizontal or substantially horizontal axis, means for imparting drive to the receivers, means for allowing end discharge from receiver to receiver, a feed provision at one end of the system, a final discharge at the opposite end 50 thereof and additional feeding means between the primary feed and the final discharge.

In testimony whereof I affix my signature.

PETER BURD JAGGER.
